CLAIM

The ornamental design for a gas fire pit as shown and described.

DESCRIPTION

FIG. 1 is a front right perspective view of the gas fire pit according to the design;

FIG. 2 is a top right perspective view thereof;

FIG. 3 is another top right perspective view thereof;

FIG. 4 is a top plan view thereof;

FIG. 5 is a front elevation view thereof;

FIG. 6 is a right side elevation view thereof;

FIG. 7 is a right side 45 degree elevation view thereof;

FIG. 8 is a rear elevation view thereof;

FIG. 9 is a top plan view thereof;

FIG. 10 is a left side elevation view thereof;

FIG. 11 is a left side 45 degree elevation view thereof; and,

FIG. 12 is another top right perspective view thereof.

In the drawings, the broken lines depict environmental subject matter only and form no part of the claimed design.
